UNITED STATES PATENT OFFICE.

DAVID HINDAHL, OF CHICAGO, ILLINOIS, ASSIGNOR TO RODGER BALLAST CAR COMPANY, OF CHICAGO, ILLINOIS, A CORPORATION OF MAINE.

DUMP-CAR.

1,398,517.

Specification of Letters Patent. Patented Nov. 29, 1921.

Application filed December 11, 1920. Serial No. 430,074.

To all whom it may concern:

Be it known that I, DAVID HINDAHL, a citizen of the United States, residing at Chicago, in the county of Cook and State 5 of Illinois, have invented certain new and useful Improvements in Dump-Cars, of which the following is a specification.

This invention relates to dump cars, and particularly to combination side and center 10 dump cars.

In railway ballast work there is great advantage in dumping the ballast material at the proper points with respect to the rails in a manner to prevent covering the 15 latter.

One object is to center and side dump ballast material in a simple, efficient and improved manner whereby the ballast material is properly deposited with respect to the rails and prevented from covering the 20 same.

Another object is to provide in a dump car means whereby the flow of dumpable material to opposite sides of a rail is accurately controlled.

Another object is to improve generally the construction of dump cars in a manner to better fit same for the severe treatment which they receive.

These and other objects are accomplished 30 by means of the arrangement disclosed on the accompanying sheets of drawings, in which—

Figure 1 is a fragmentary side elevation 35 of a railway dump car embodying my invention;

Fig. 2 is a transverse sectional view of the same dump car showing the door structure arranged for center dumping;

Fig. 3 is a similar transverse sectional view of the same dump car showing the door structures arranged for side dumping;

Fig. 4 is a fragmentary plan view of the same car, some floor parts being removed 45 for the sake of clearness; and,

Fig. 5 is a detail top plan view of the side stake securing means.

The various novel features of my invention will be apparent from the following 50 description and drawings and will be particularly pointed out in the appended claims.

Referring to the figures of the drawings, it will be noted that my invention is illustrated in connection with a dump car hav-

ing sides 10, ends 11 and a bottom, which 55 in this case is a hopper bottom, there being two hoppers 12 formed on opposite sides of the center sill structure 9, the latter including downwardly extending vertical members 8 from the lower ends of which 60 downwardly and outwardly inner stationary sloping hopper side walls 13 extend. For overcoming the restricting effect of outer flanges overhanging the sill members 8 and 65 for increasing the effective hopper dumping width, an inverted channel 7 is inserted between the upper edges of member 8. The lower ends of the downwardly and outwardly sloping members 13 are braced by cross bracing members 13'. The other walls 70 of the hoppers 12 are composite in construction and take the form of door structures to be referred to more particularly herein-after, and vertically arranged frame members 6 extending longitudinally between and 75 secured to adjacent cross frame member 6' by suitable brackets 5. The lower edges of these frame members 6 are turned inwardly to protect the adjacent hinges 19 to be referred to later. The car shown is 80 of a convertible nature in that a flat floor is provided including movable members 14 which, as shown in the figures of the drawings, may take an inclined position in which they are supported by the car sides to form 85 hopper side walls. These members 14 are movable into horizontal position to form portions of a continuous flat floor, of which floor members 15 form a part. The car sides 10 also include side wall doors 16, which 90 are pivoted along their upper edges at 17, whereby such doors 16 may swing outwardly, with a flat floor arrangement, for dumping at least a portion of the lading to the sides of the car. In this connection 95 attention is called to the fact that these cars, when arranged as flat bottom cars, are unloaded through the side doors 16 by plows which are drawn through the cars from end to end, forcing the lading outwardly. 10 Such unloading plows at times do considerable damage to the side stakes 30 which extend into the loading space. To support and reinforce these stakes in an improved manner, I have provided same with channel-shaped rub plates 31 which are secured to the stakes and to brackets 32 which in turn are secured to the side sills 33.

Particular reference will now be had to means whereby the flow of dumpable material from the hoppers 12 may be accurately controlled, and more specifically to means 5 whereby ballast material is properly deposited with respect to the rails and prevented from covering the latter.

As mentioned hereinabove, the center sill members 13 form inner walls of the longitudinally extending hoppers 12. The other, or outer, walls of these hoppers 12 are formed by door structures in each case, including a door frame 18 pivotally connected at its upper edge as at 19 to any suitable 10 bracket or support 20. The door frame 18 in each case extends considerably beyond the lower extremity of its associated hopper side wall 13 when in closed position, as 15 shown in Fig. 3. The opening and closing 20 movements of the door frames are controlled by any suitable door operating mechanism including links 21 operatively connected to said door frames and to chains 22 coöperating with an operating shaft 23. Pivotally 25 mounted in each of these door frames is one or more doors 24 which preferably are pivoted in the door frame as at 25 at a point just below the lower extremity of the associated inner hopper side wall 13 so that 30 when the doors 24 are in an open position, as shown in Fig. 3, the doors 24 and the inner hopper walls 13 form a continuous shedding surface which may or may not be in the same plane, in accordance with requirements. 35 These doors 24 are controlled by any suitable door operating mechanism, including chains 26 operatively connected to the doors and to operating shafts 27. Forming a part of each of the door structures 40 is a downwardly and inwardly extending shedding plate 28 which is located within the upper half of the door frame 18, the lower edge of which plate is spaced from the lower extremity of the associated inner 45 hopper side wall 13 to provide a restricted dumping exit 29 whereby the control of the flow of the dumpable material to the outer sides of the rails is made more efficient.

50 As shown in Fig. 3, of the drawings, the door frames proper are held in closed position and the doors 24 pivotally mounted in said frames are in open position whereby dumpable material is directed to the outer 55 sides of the rails. It will be noted that the outer edges of the doors 24 are located directly outside of the rails for definitely positioning the dumpable material or ballast where it is to be used and in a manner 60 such that the ballast will not cover the rails. With the doors 24 in the open position it will be appreciated that were the exit opening 29 not restricted by the plates 28 or equivalents thereof, the dumpable material 65 would flow outwardly in a less con-

trolled manner, causing such material to rush outwardly far beyond the outer edges of the rails. In this same connection it will be appreciated that no dumpable material will be dumped to the side of a car 70 until the doors 24 are considerably below the horizontal position and in this manner the members 28 aid in preventing an initial rush of the dumpable material to a point far beyond the outer sides of the rails. 75

It will be understood that when it is desired to center dump, the doors 24 will occupy a closed position with respect to the door frames 18, as shown in Fig. 2. This figure shows the door structures in open 80 position for controlling the depositing of the ballast between the rails and in a manner to prevent such ballast from covering the rails. The lower edges of the door frames 18 lie a considerable distance within the rails and a less distance above the same so that there is little or no possibility of any ballast material covering the rails. With the parts in the position shown in Fig. 2, it will be noted that the control 90 plates 28 do not form the restricting function as they do in connection with side dumping, these control plates forming a part of the door frame and being movable therewith. The inner hopper side walls 95 13, however, coöperate with the door structures for center dumping to restrict the flow of dumpable material in a manner whereby the flow is more controlled than otherwise would be the case. 100

In effect, in this combination center and side dump arrangement, there is provided a door within a door, the main door comprising the whole door structure in each case, which is moved into an open position 105 with respect to the car, while the auxiliary doors 24 are in closed position with respect to the door frames for center dumping, as shown in Fig. 2. For side dumping, each of the door frames 18 is in closed position 110 with respect to the car, while the auxiliary door 24, which is the door within a door, in each case is in an open position, as shown in Fig. 3.

It is my intention to cover all modifications of the invention falling within the spirit and scope of the following claims. 115

I claim:

1. A car of the class described having a bottom comprising a longitudinally extending hopper, said hopper having an inclined stationary side and an inclined movable side, said movable side including means for directing the load discharged from the hopper to one side or to the other side of a 120 rail.

2. A car having a bottom comprising a longitudinally extending hopper, one side of said hopper being stationary and inclined downwardly, the other side of said hopper 125 130

including an inclined door normally engaging the stationary side and mounted to swing away from said stationary side to discharge the load to one side of the rail or to 5 swing into line with said stationary side to discharge the load to the other side of the rail.

3. A car of the class described having a bottom comprising a longitudinally extending 10 hopper, said hopper having an inner stationary side and an outer movable side, said movable side being adapted to discharge the load to one side of the rail and including means for directing the load of 15 the hopper to the other side of the rail.

4. A dump car having sides, ends and a bottom, the latter including a door structure pivotally mounted for directing dumpable material to one side of a rail and having 20 a door pivotally mounted therein for directing such material to the other side of said rail when said door is in an inclined position.

5. A dump car having sides, ends and a bottom, the latter including a door structure pivotally mounted at its upper end and movable to control the flow of dumpable material to a point between the rails and having 25 a pivotally mounted door for directing such material to the outer side of a rail when said door is an inclined position.

6. A dump car having sides, ends and a bottom, the latter including a movably mounted door structure with a door pivotally mounted therein whereby dumpable material is either directed to one side of the rail by the door structure and door or to the other side of the rail by the door when in a different inclined position.

40 7. A dump car having sides, ends and a bottom, the latter including a movably mounted door structure with a door pivotally mounted therein whereby dumpable material is either directed to one side of the rail by the door structure and door or to the other side of the rail by the door when in a different inclined position, and operating mechanisms for said door structure and door.

50 8. A dump car having sides, ends and a bottom, the latter having a door structure including a door which when in a given position directs the flow of dumpable material to a given position with respect to a rail, said door structure including means for restricting the flow of such dumpable material to said flow directing door.

60 9. A dump car having sides, ends and a bottom, the latter including a door frame and a door pivotally mounted therein whereby dumpable material may be directed to a given position to one side of the rail, and means associated with said door frame for restricting the exit opening associated with 65 said door.

10. A dump car having sides, ends and a bottom, the latter including a door frame and a door mounted therein, the door frame with the door being tilttable in one direction for controlling the flow of dumpable material between the rails and the door being tilttable in a different direction for directing the flow of dumpable material to the outer side of the rail. 70

11. A dump car having sides, ends and a bottom, the latter including a stationary hopper side and a movable hopper side, the latter including a door frame and a door mounted in said frame, the frame when in closed position terminating at a point beyond said stationary hopper side wall and when open controlling the supply of dumpable material to a point between the rails, said door when open with the door frame in closed position directing dumpable material to the outer side of the associated rail. 80

12. A dump car having sides, ends and a bottom, the latter including a stationary hopper side and a movable hopper side, the latter including a door frame and a door mounted in said frame, the frame when in closed position terminating at a point beyond said stationary hopper side wall and when open controlling the supply of dumpable material to a point between the rails, said door when open with the door frame in closed position directing dumpable material to the outer side of the rail, and means for restricting the exit opening when the material is being dumped to the outer side 90 of the rail. 95

13. A dump car having sides, ends and a bottom, the latter including downwardly and outwardly extending stationary hopper portions and downwardly and inwardly movably mounted door frames having doors movably mounted therein for selectively controlling the flow of dumpable material between the rails and to the outer sides of 105 said rails. 110

14. A car of the class described having a center sill forming wall portions of oppositely arranged hoppers, said center sill including longitudinally extending members, and a channel member secured therewithin for preventing a restriction of the dumping opening by avoiding outwardly extending flanges. 115

15. A car of the class described having a center sill forming wall portions of oppositely arranged hoppers, said center sill including longitudinally extending members, a channel member secured therewithin for preventing a restriction of the dumping opening by avoiding outwardly extending flanges, and means for bracing the lower ends of said longitudinally extending members. 120 125

16. A car of the class described including a center sill having downwardly and out- 130

wardly extending members forming hopper side walls, a channel member secured there-
within for preventing a restriction of the
dumping opening by avoiding outwardly
extending flanges, and a brace between the
outwardly extending portions of said mem-
bers for reinforcing same.

17. A car of the class described, having a
bottom comprising a substantially V-shaped
hopper, one of the sides of said hopper ex-
tending beyond the edge of the other side
at the apex of the hopper.

18. A car of the class described, having a
bottom comprising a substantially V-shaped
hopper having a downwardly and outwardly
inclined inner side and a downwardly and
inwardly inclined outer side, the inner end
of said outer side extending beyond the
lower edge of the inner side, and means for
discharging the load through said hopper.

19. A car of the class described, having a
bottom comprising a substantially V-shaped
longitudinal hopper, one of the sides of said
hopper being hinged to swing toward and
away from the other side to discharge the
load, the lower edge of said swinging side
extending beyond the lower edge of the
other side when in closed position.

20. A car of the class described, having a
bottom comprising a substantially V-shaped
hopper having a downwardly and outwardly
inclined inner side and a downwardly and
inwardly inclined outer side, the inner end
of said outer side extending beyond the
lower edge of the inner side, and means for
discharging the load through said hopper
toward the center or toward the side of the
car.

21. A car of the class described, having a
bottom comprising a substantially V-shaped
longitudinal hopper, the inner side of said
hopper extending downwardly and out-
wardly toward the sides of the car, the outer
side of said hopper extending downwardly
and inwardly toward the center of the car,
said outer side being hinged at its upper
edge to swing toward and away from the
inner side, and extending when in closed

position beyond the lower edge of said inner
side.

22. A car of the class described, having a
bottom comprising a longitudinally extending
hopper, one side of said hopper being
formed of an inclined stationary member,
the other side of the said hopper being
formed of an inclined swinging member
hinged at its upper edge and swinging away
from and toward the stationary member,
and contacting with said stationary member
to form an approximately V-shaped hopper,
the inner end of said swinging member ex-
tending beyond the edge of the stationary
member when in closed position.

23. A car of the class described, having a
bottom comprising two parallel longitudi-
nal hoppers, one side of each of said hop-
pers being formed of an inclined stationary
member, the other side of each of said hop-
pers being formed of an inclined swinging
member, said swinging members being
hinged at their upper edges to swing toward
and away from said stationary members and
forming in closed position substantially
V-shaped hoppers said swinging members
including doors movable downwardly into
line with said stationary members and
means for simultaneously operating said
swinging members.

24. A car of the class described, having a
bottom comprising two parallel longitudinal
hoppers, one side of said hoppers being
formed with an inclined stationary member,
the other side of said hoppers being formed
with an inclined swinging member, said
swinging members being hinged at their
upper edges to swing away from and toward
the said stationary members, and forming
in closed position substantially V-shaped
hoppers, the inner edges of said swinging
members extending beyond the edges of the
stationary members when in closed position,
and means for simultaneously operating said
swinging members.

Signed at Chicago, Illinois, this 7th day
of December, 1920.

DAVID HINDAHL.
